(57) **CLAIM**

We claim the ornamental design for dining chair, as shown and described.

DESCRIPTION

FIG. 1 is a perspective view of a dining chair of the invention.

FIG. 2 is a rear view of a dining chair of the invention.

FIG. 3 is a front view of a dining chair of the invention.

FIG. 4 is a side view of a dining chair of the invention, the view from the opposite side being a mirror-image thereof; and,

FIG. 5 is an overhead view of a dining chair of the invention.

The dashed lines showing portions of the chair legs are for illustrative purposes only and form no part of the claimed design.

The shading on the seating surface and portions of the chair back illustrates a contrasting color visually darker than the balance of the chair.
